UNITED STATES PATENT OFFICE.

VINCENT G. ANDERSON, OF KENOSHA, WISCONSIN, ASSIGNOR, BY MESNE ASSIGNMENTS, TO F. C. AUSTIN MACHINERY COMPANY, A CORPORATION OF ILLINOIS.

WALKING MOTION PROPELLING APPARATUS.

Application filed April 22, 1918. Serial No. 229,945.

To all whom it may concern:

Be it known that I, VINCENT G. ANDERSON, a citizen of the United States of America, and resident of Kenosha, county of Kenosha, and State of Wisconsin, have invented a certain new and useful Improvement in Walking Motion Propelling Apparatus, of which the following is a specification.

This invention relates to propelling apparatus of that kind in which the structure as a whole is so constructed and operated that it has a walking motion, being constructed to move forward intermittently, the weight being first supported on the main frame or body and then on the auxiliary frame in a manner which is characteristic of apparatus of this kind.

Generally stated, the object of the invention is to provide a novel and improved apparatus of the foregoing general character.

A special object is to provide a novel and improved means for intermittently shifting the main frame or body above the ground, and for shifting the auxiliary frame in a similar manner, practically by one and the same mechanism; to provide an improved construction and arrangement whereby the main frame or body, and also the auxiliary frame, may be rotated about a vertical axis, by means of a turn-table, thereby to facilitate the work of handling and shifting the structure in the desired direction; and to provide certain details and features of construction and combinations tending to increase the general efficiency and desirability of a propelling apparatus of this particular construction.

Apparatus of this kind can be used for various purposes, and may be employed, for example, for propelling a large and heavy excavator forward along the ground, such as an ordinary drag-line bucket excavator, but the invention is not limited to any particular use or purpose.

To the foregoing and other useful ends, the invention consists in matters hereinafter set forth and claimed, and shown in the accompanying drawings, in which:

Figure 1 is a side elevation of a walking motion propelling apparatus embodying the principles of the invention, showing both the main frame and the auxiliary frame resting on the ground.

Figure 2 shows the auxiliary frame in

raised position, and partially moved forward, being in position to complete its forward movement by the operation of the shifting mechanism.

Figure 3 shows the forward motion of the auxiliary frame completed, and shows this auxiliary frame lowered to the ground in its advanced position.

Figure 4 shows the main frame or body of the excavator in raised position, and partially shifted forward, being in position to complete its forward movement by the further operation of the shifting mechanism.

Figure 5 is a plan of a portion of the structure shown in said preceding views, the parts being in the positions shown in Figure 1, and some of the upright portions being shown in horizontal section, and other parts being broken away, to more clearly illustrate the construction of the shifting apparatus.

As thus illustrated, the invention comprises a main frame or body composed of trussed or otherwise strengthened side frames 1, suitably connected together by cross-members 2, so that a strong and rigid frame is provided of the desired size and shape. This frame is supported by rollers 3, some of which are provided with cog-teeth, to travel on the rack 4 of the turn-table 5, the latter being supported by hangers 6 on the body 1, these hangers having rollers 7 which engage the lower track 8 within the turn-table, whereby the latter may be raised from the ground with the body 1 of the excavator or other structure. The cog-wheels 3 may have rollers 9 associated with the teeth to carry the weight on the smooth circular tracks of the turn-table, and any suitable power-transmitting connections, leading from an engine or motor (not shown) can be employed for operating these pinions or cog-wheels to turn the body 1 about a vertical axis, on the turn-table, in a manner that will be readily understood.

The auxiliary frame comprises upright members 10 at opposite sides of the main frame or body, the latter having a slot or longitudinal space 11 at each side thereof in which the two auxiliary frames are adapted to have relative movement longitudinally of the structure. The two upright members 10 are connected together at their upper ends by a longitudinal brace or member 12, and

below by upper and lower racks 13 and 14, and the lower ends of the members 10 rest on a longitudinally disposed shoe or sled-runner 15 which rests on the ground; and 5 the two members 10 at the opposite side of the main frame or body are connected together and mounted and arranged in the same manner. The main frame or body is provided with a transverse shaft 16, extending 10 underneath said frame, and the ends of this shaft, which is mounted in bearings 17, are provided with segmental pinions 18 to engage the teeth of said racks. Any suitable power-transmitting-connection can be 15 employed to transmit power from an engine or motor to the shaft 16, to operate the segmental pinions 18, and to thereby alternately lift and lower the auxiliary frame having the shoes 15, and to alternately lift and 20 lower the main frame comprising the side frames 1, thereby to produce the walking motion, which is substantially as follows:—

In Figure 1 the turn-table 5 is resting on the ground, and the shoes 15 are also resting 25 on the ground. Rotation of the shaft 16, to operate the pinions 18 in the direction indicated by the arrow, will disengage the segmental pinions 18 from the lower racks 14 and will cause the upper racks 13 to travel 30 forward on the teeth of the segmental pinions. This results, of course, in the raising of the auxiliary frame having the shoes 15, so that said frame and shoes assume the position shown in Figure 2, and further 35 rotation of the segmental pinions finally lowers the auxiliary frame to the ground again, but in an advanced position, as shown in Figure 3; and the operation of the shifting mechanism continuing, the segmental pinions 18 will then travel forward upon 40 the teeth of the racks 14, until these pinions assume the position shown in Figure 4, thereby raising the main frame or body, and also the turn-table 5, so that the entire 45 weight of the main frame and the auxiliary frame is now supported by the shoes 15, and whereby the main frame or body is brought into an advanced position. By continuing 50 the operation of the mechanism, the main frame or body comprising the side frames 1 and the turn-table 5 will then move forward a distance, and will then be lowered to the ground, as shown in Figure 1, so that the main frame or body will be brought into 55 its farthest or most advanced position, by two steps forward, the auxiliary frame having been shifted forward one step, and the main frame or body having been shifted forward one step; and this operation is repeated, 60 it will be understood, until by this walking motion the excavator or other structure or machine is caused to travel forward the desired distance.

The turn-table 5 can be supported on the 65 ground by any suitable means, by shoes, or

by a flat bottom, as may be desired, and depending upon the character of the work and requirements of the different situations. In any event, though, it will be seen that with a propelling apparatus of this kind a large 70 and very heavy body can be shifted or caused to travel from one place to another, over soft ground, and over stretches of territory which would make it impractical to endeavor to use wheels or caterpillars or other similar devices. Also, a shifting apparatus of this kind can be manufactured or constructed in a very inexpensive manner, so that the cost 75 is less than would be required with other types of traction or propelling devices. 80

Furthermore, with the construction shown and described, which is illustrative of the invention, the shifting mechanism is comparatively simple, and the up-and-down movements and the forward movements are 85 produced by one and the same mechanism, whereas with certain other types of walking motion propelling apparatus one set of devices is necessary for lifting or shifting the main frame or body, and another set of devices is necessary for lifting and shifting the auxiliary frame, and in some cases the apparatus is quite complicated. With the construction shown and described, however, involving the racks 13 and 14, and the segmental pinions 18, which are illustrative of and embody the principles of the invention, the walking motion is continuous, so to speak, inasmuch as the rotation of the shaft 16 is all that is necessary to raise and shift 90 both the auxiliary frame and the main frame, and this intermittent walking motion is maintained as long as the shaft is rotated, and in this way one mechanism or one set of devices is practically sufficient to produce 95 the walking motion. 100

It will be understood that in the various figures of the drawings the front and rear ends of the main frame or body are shown broken away for convenience of illustration, but said body may be of any suitable or desired length, and it will be seen that the weight thereof is so well balanced by the shifting mechanism that while the main frame or body is being shifted the entire 110 weight is supported by the shoes 15, at least for a portion of the forward shifting motion thereof. This is also true of the auxiliary frame, for at certain times it is entirely off the ground, and is supported by the main frame or body. However, the shoes for the bottom of the turn-table and the auxiliary frame can be of such character that they will slide readily forward on the ground, if there is any teetering or tilting or dragging motion of either the main frame or the auxiliary frame which might occur, for example, during the initial lifting of either the main frame or the auxiliary frame, or during the final forward shifting 125 130

motion of either frame. In any event, though, as shown and described, the walking motion is produced by comparatively simple means, and by reason of the turn-table, when 5 the auxiliary frames are raised from the ground, the main frame or body can be swung around about a vertical axis, and in this way the direction of travel can be changed at will.

10 It will be seen that the auxiliary frame preferably comprises two frame sections, each frame section including a shoe 15 and the risers or upright members 10 mounted thereon, and the two frame sections being 15 disposed at opposite sides of the main frame or body of the excavator or other structure. But, with the mechanism shown and described, the two auxiliary frame sections move forward in unison, and are raised and 20 lowered in unison, in a manner that will be readily understood.

With the construction shown and described it will be seen that the side frames (10, 12, 13, 14) form an auxiliary frame 25 which is movable up and down in the main frame 1, so that this auxiliary frame is held against lateral displacement, being guided up and down by the structure of the main frame, in a manner that will be readily understood. The turn-table is disposed between the two side frames, and supports the entire structure when it is on the ground, but the said turntable is in turn supported by the auxiliary frame when the main frame 35 is raised from the ground.

What I claim as my invention is:—

1. A walking motion propelling apparatus, comprising a main supporting frame, an auxiliary frame mounted for vertical 40 movement with respect to said main frame, a rotary actuating member on the main frame, and spaced sections on the auxiliary frame adapted to be alternately engaged by said actuating member, engagement of one 45 of said sections serving to successively lift the auxiliary frame to a substantial height above the ground, shift it horizontally forward and lower it again onto the ground, and engagement with the other section serving to similarly control the main frame 50 to accomplish a forward step movement thereof.

2. A walking motion propelling apparatus comprising a main frame, side frames 55 forming an auxiliary frame arranged to move up and down in the main frame, means to support the main frame on the ground, means to support the auxiliary frame on the ground, and mechanism adapted by continuous operation thereof to alternately lift 60 said frames, so that said frames alternately support each other, thereby to intermittently propel them forward, whereby each frame moves forward horizontally while the other 65 is stationary, said mechanism comprising

upper and lower racks on the auxiliary frame disposed below the tops of both frames, and a segmental pinion carried by the main frame and adapted to alternately engage said racks, so that the pinion engages the lower rack to lift the main frame and engages the upper rack to lift the auxiliary frame. 70

3. A walking motion propelling apparatus comprising a main frame, side frames forming an auxiliary frame arranged to move up and down in the main frame, means to support the main frame on the ground, means to support the auxiliary frame on the ground, and mechanism adapted by continuous operation thereof to alternately lift said frames, so that said frames alternately support each other, thereby to intermittently propel them forward, whereby each frame moves forward horizontally while the other is stationary, said mechanism comprising spaced horizontal racks on the auxiliary frame and a rotary toothed segment on the main frame disposed between and adapted to alternately engage said racks to successively lift and advance said main and auxiliary frames. 80 85 90

4. A walking motion propelling apparatus comprising a main frame, side frames forming an auxiliary frame arranged to move up and down in the main frame, means to support the main frame on the ground, means to support the auxiliary frame on the ground, and mechanism adapted by continuous operation thereof to alternately lift said frames, so that said frames alternately support each other, thereby to intermittently propel them forward, whereby each frame moves forward horizontally while the other is stationary, said mechanism including an upper rack, a lower rack, and a pinion to alternately engage said racks, so that said pinion engages one rack to lift the main frame and engages the other rack to lift the auxiliary frame. 95 100 105 110 115

5. A walking motion propelling apparatus comprising a main frame, side frames forming an auxiliary frame movable up and down in the main frame, a rotary actuating member on the main frame, spaced sections on the auxiliary frame above and below said member and adapted to be successively engaged thereby to alternately lift said frames and propel them forward horizontally, so that the weight of the structure is first on one frame and then on the other, to produce a walking motion, and a turn-table carried by the bottom of the main frame, between the two side frames, whereby the entire structure may be turned about a vertical axis 120 when the auxiliary frame is lifted from the ground. 125

6. A structure as specified in claim 5, said auxiliary frame comprising a shoe at each side of the main frame, with frame mem- 130

bers extending upward from each shoe, so that the auxiliary frame is composed of two frame sections, the main frame being movable up and down on said members, and said turn-table being disposed between said frame sections of the auxiliary frame.

7. A walking motion propelling apparatus comprising a main frame, a turn-table base below said main frame, means on the main frame to lift the turn-table base, when the main frame is raised, means to support the main frame for rotary motion on the turn-table base, side frames forming an auxiliary frame, means to support the auxiliary frame on the ground, an upper rack on each side frame, a lower rack on each side frame, a transverse shaft journaled on the main frame, and a segmental pinion disposed on said shaft at each side of the main frame, said pinions being adapted to engage said racks to move the side frames up and down in said main frame, thereby causing the main frame and the auxiliary frame to alternately move forward, said main frame hav-

ing side portions which prevent lateral displacement of said auxiliary frame.

8. In apparatus of the character described, the combination of a turn-table base, a body frame, means on said body frame to lift said turn-table base, when the body frame is raised, said means being disposed at different points adjacent to the outer sides of said base, means on the body frame to travel on the turn-table base when the latter rests on the ground, and means for lifting the body frame to raise the turn-table base from the ground, and for moving the frame and turn-table forward a distance.

9. A structure as specified in claim 8, said means for lifting the turn-table base comprising hangers on the body frame, a circular track on said base, and means on the lower ends of said hangers to engage the under side of said track.

Signed by me at Chicago, Cook County, Illinois, this 23rd day of March, 1918.

VINCENT G. ANDERSON.
